Primary Examiner — Katie Jane Stofko*(74) Attorney, Agent, or Firm* — Troutman Pepper Hamilton Sanders LLP; Christopher C. Close, Jr.; Chris N. Davis(57) **CLAIM**

I claim the ornamental design for an apple donut with a coating, as shown and described.

DESCRIPTION

FIG. 1 is a front, top and right side perspective view of an apple donut with a coating, in accordance with the present invention;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.
